[57] CLAIM

The ornamental design for a cartridge for protective
film overlay of a recording head in a xerographic
printer, as shown.

DESCRIPTION

FIG. 1 is a front elevational view of a cartridge for
protective film overlay of a recording head in a xero-
graphic printer showing my new design;

FIG. 2 is a left side elevational view;

FIG. 3 is a top plan view;

FIG. 4 is a right side elevational view;

FIG. 5 is a bottom plan view; and

FIG. 6 is a rear elevational view.

FIG. 4

FIG. 3

FIG. 1

FIG. 2
